UNITED STATES PATENT OFFICE.

FLOYD J. FRANCE AND PETER F. CRAUN, OF QUINCY, MICHIGAN.

HORSESHOEING APPLIANCE.

Specification of Letters Patent. Patented Sept. 10, 1918.

1,278,628.

Application filed October 11, 1917. Serial No. 195,955.

To all whom it may concern:

Be it known that we, FLOYD J. FRANCE and PETER F. CRAUN, citizens of the United States, residing at Quincy, in the county of Branch and State of Michigan, have invented certain new and useful Improvements in Horseshoeing Appliances, of which the following is a specification.

This invention relates to farriery and has 10 more especial reference to an improved horseshoeing appliance.

The invention has for its dominant object to provide a hoof supporting device adapted for use by farriers, whereby a horse's foot 15 will be supported in a manner and position such as will allow shoeing thereof in a rapid and efficient manner.

Another object of the invention is to provide a device of the character mentioned 20 whereby the hoof of a horse will be resiliently supported, thereby allowing the shock incident to the nailing of the shoe upon the hoof to be fully absorbed.

The foregoing together with additional 25 advantageous details and arrangement of parts of the preferred embodiment of my invention will be clear from the specific description hereinafter contained, when read in connection with the accompanying drawings 30 forming part thereof, wherein said embodiment of the invention is illustrated for the purpose of facilitating a full understanding of the present improvements.

In the drawings:

35 Figure 1 is a vertical longitudinal section through the improved support;

Fig. 2 is a transverse section therethrough;

Fig. 3 is a detail partly in section showing the modified form of accessory; and

40 Fig. 4 is a detail in elevation of another modified form of accessories.

Having more particular reference to the drawings and in connection with which like reference characters will refer to corresponding parts in the several views, 1 represents a hollow standard, the lower extremity of which is externally screw-threaded and received in a multiple-legged stand 2. Over the upper end of the tubular standard 1 there 45 is arranged an annular cap 3 having an opening formed in one side thereof whereby a pivotal pawl 4 may be arranged therein, the said pawl being normally held under tension through the medium of a coiled spring 5 arranged in the said cap and having bearing 50 on the pawl. Rivets 6 or other suitable fas-

tening devices are passed through the lower end of the cap 3 into engagement with the standard 1, serving as means for securing the cap thereto.

Slidably received in the hollow standard 1 is a shaft 7, substantially rectangular in cross-section and having one marginal edge thereof provided with a series of teeth 8, the purpose of which will be subsequently obvious. The upper end 9 of the shaft receives thereover a head 10, the upper end of which is rounded as at 11. To resiliently support the head 10 upon the upper end of the shaft 7 a coiled spring 12 is arranged upon the reduced end 9 and, as shown in Fig. 1, engages the under side of the top of the said head 10. Slots 13 are formed in the lower portion of the head 10 at opposite points and receive the extremities of pins carried upon the adjacent portion of the shaft 7, thus limiting the movement of the head with relation to the shaft. Upon the outer sides of the head 10 there are formed a plurality of diagonally disposed ribs 14, which ribs serve as means 80 for securing accessories hereinafter fully described in position upon the shaft 7.

A support 15 having a concaved upper portion is provided and carries a collar 16, the inner surfaces of which are provided with other diagonally disposed ribs 17 adapted to be engaged with the ribs 14 formed upon the head 10 when the support is turned into engagement therewith.

There is also provided a bracket 18, the 90 same having formed upon the upper end of the vertical shank thereof a rest 19, while the lower end of the shank is provided with a collar having diagonally disposed ribs 20 formed upon its inner surface, which ribs 95 may be engaged with the ribs 14 on the head 10 by turning the same thereupon. The bracket or support 18 serves as means for facilitating the handling of bars of iron, it of course being understood that one end of a bar is arranged upon the anvil at which the farrier is working while the other end is arranged upon the rest 19 of the support. In this way, the services of a helper will be dispensed with.

In Fig. 4 there is disclosed another modified form of attachment for the appliance, the same including a shank 21 having a ratchet face 22 formed upon one marginal edge thereof, the teeth of which are adapted 100 to be engaged by the pawl 4. The upper extremity of the shank 21 is bifurcated to pro-

vide bearing members and receive a roller 23 therein, the said roller having trunnions arranged upon the opposite ends of the same. With this attachment, bars of iron may 5 be readily handled by a single man, one end of the bar resting upon the anvil and the other end resting upon the roller 23. Thus, when it is desired to move the same forwardly it is only necessary to roll the bar of 10 iron.

When using the improved horseshoeing appliance, the shaft 7 is permitted to lower in the hollow standard 1, whereupon the lower end of the head 10 will rest upon the 15 top of the cap 3, thus forming a rigid support therefor. The horse's leg is now placed upon the rest 15 which has been previously turned into engagement with the head 10 and the old shoe removed and the hoof pared 20 or trimmed in order that the new shoe will seat flush thereon. Subsequent to the trimming of the hoof it is desired to place the new shoe thereon, whereupon the shaft 7 is raised to the proper height in the standard 25 and the pivotal pawl 4 engaged with one of the teeth 8 formed on the said standard. By so adjusting the shaft, it will be appreciated that a resilient support will be provided for the leg of the horse and as a consequence, all shock transmitted to the hoof 30 of the animal during the nailing of the shoe thereon will be absorbed by the spring 12. After the shoe has been placed on the hoof 35 and it is desired to file or rasp the same to remove the surplus portions of the hoof, the shaft 7 is again lowered into the standard and the rest 15 disengaged from the head 10, whereupon the hoof of the horse may be placed upon the rounded surface 11 of the 40 said head and supported thereon during the rasping of the same.

Copies of this patent may be obtained for five cents each, by addressing the "Commissioner of Patents, Washington, D. C."

With our improved appliance, it will be readily appreciated by those skilled in the art that we eliminate the heretofore laborious work incident to horseshoeing operations, wherein the farrier supported the horse's leg in a position to allow the placing of the shoe upon the hoof. 45

Manifestly, the construction shown is capable of considerable modification, and such 50 modification as is within the scope of our claims we consider within the spirit of our invention.

We claim:—

1. A device of the character described, including a hollow standard, a shaft movably received in the standard having a series of teeth formed upon one edge thereof, a pivoted pawl on the standard engageable with said teeth for securing the shaft in adjusted 55 positions in the standard, a head slidably supported on said shaft, resilient means interposed between the head and the adjacent end of the shaft, and a rest detachably engaged with said head. 60

2. A device of the character described, including a hollow standard, legs for supporting said standard, a shaft movably received in the standard and having a series of teeth formed upon one edge thereof, a pivoted 70 pawl on the standard engageable with the teeth on said shaft, a head having a rounded upper end slidably received on the upper end of said shaft, resilient means interposed between said head and the adjacent 75 end of said shaft, and a rest detachably engaged with the head.

In testimony whereof, we affix our signatures hereto.

FLOYD J. FRANCE.
PETER F. CRAUN.
